CLAIMThe ornamental design for a shoe midsole, as shown and described.DESCRIPTIONFIG. 1 is a front perspective view of a shoe midsole showing my new design;

FIG. 2 is a side view thereof; and,

FIG. 3 is a rear perspective view thereof.

The broken lines immediately adjacent to the shaded area represent unclaimed boundaries of the design. The broken lines showing the remainder of the shoe are for environmental purposes only and form no part of the claimed design.1 Claim, 3 Drawing Sheets(56)
